(57) **CLAIM**

The ornamental design for a lamp with a shade and a base as shown and described.

DESCRIPTION

FIG. 1 is a top perspective view of a lamp with a shade and a base.

FIG. 2 is a bottom perspective view thereof.

FIG. 3 is a front side elevation view thereof.

FIG. 4 is a rear side elevation view thereof.

FIG. 5 is a left side elevation view thereof.

FIG. 6 is a right side elevation view thereof.

FIG. 7 is a top view thereof; and,

FIG. 8 is a bottom view thereof.

Broken lines in the drawings illustrate portions of the base that form no part of the claimed design.
